UNITED STATES PATENT OFFICE.

JOHN MEAD, OF DETROIT, MICHIGAN.

HYDRANT.

SPECIFICATION forming part of Letters Patent No. 349,230, dated September 14, 1886.

Application filed February 25, 1886. Serial No. 193,107. (No model.)

To all whom it may concern:

Be it known that I, JOHN MEAD, of Detroit, in the county of Wayne and State of Michigan, have invented new and useful Improvements 5 in Hydrants; and I do hereby declare that the following is a full, clear, and exact description thereof, reference being had to the accompanying drawings, which form a part of this specification.

10 My invention relates to a new and useful improvement in hydrants; and it has particular reference to that class of hydrants known as "fire-plugs" or "fire-hydrants."

15 The most improved fire-hydrants known in the state of the art at the present day are provided, in addition to the main valve, with what is called a "supplemental valve," the principal object of which is to permit the removal of a hydrant for the purpose of repair 20 or otherwise without shutting off the water from the main, said supplemental valve being so arranged that it works automatically and without interfering with the function of the main valve.

25 In the following specification I describe as part of my invention a supplemental valve of an improved construction, which I consider to present decided advantages over the constructions now in use or known and of which I 30 have any knowledge. Farther on I also describe an improved construction of the waste-valve, which forms an essential part of all fire-hydrants by permitting the water remaining in the stock of the hydrant after the water is shut 35 off to leak into the ground, thus preventing the hydrant from freezing up in cold weather.

In the drawings which accompany this specification, Figure 1 is a vertical central section of my improved hydrant. Fig. 2 is a more 40 enlarged vertical central section showing only the lower end of the hydrant, in which the waste-valve is located. Fig. 3 is a horizontal cross-section on the line $\alpha\alpha$ in Fig. 2.

A is the stand-pipe or stock of the hydrant. 45 B is the cap, removably secured thereon. C is a loose spindle supported by the cap and provided with a female thread engaging with the male thread upon the upper end of the valve-rod D. E is a nut arranged to keep the spindle C in place. F is a stuffing-box, through 50 which the valve-rod passes. G is the discharge-nozzle. H is the main valve, and I is

the frost-case, all these parts being of any known construction and forming no part of my invention.

55 K is the elbow connecting the hydrant with the water-main and forming the base upon which it is supported.

L is the supplemental valve. It is located in the horizontal arm of the elbow, and is secured upon a central valve-stem, M, which slides horizontally in bearings $a a$, which permit a sufficient movement of the valve to open and close the latter freely. These bearings are formed by brass bushings supported by 60 suitable bridges, $b b'$. I construct the elbow preferably with a short removable section, K', which is bolted onto the main section of the elbow, and by locating the bridge b in one section of the elbow and the bridge b' in the other 65 the supplemental valve can be readily removed by taking the two sections apart. Any other construction for this purpose may be used, however.

70 N is a bell-crank located within the bend of the elbow. It is secured by means of the pivot-pin c in a recess, d , formed in the angle of the elbow, all so arranged as to permit the bell-crank to turn freely in a vertical plane, for the purpose hereinafter described. The arms of 75 the bell-crank are at right angles to each other, or nearly so. Its vertical arm is held in contact by gravity against the inner end of the valve-stem M, and its horizontal arm extends in proximity to the lower end of the main 80 valve, but does not make contact therewith when the main valve is fully closed, as shown in Fig. 1. When, however, the main valve is slightly opened by turning the spindle with a suitable key, as in the usual manner, such contact is established and then the further operation of opening said main valve communicates motion to the bell-crank and transmits it to the valve-stem of the supplemental valve, thus 85 forcing the latter from its seat and admitting 90 water into the hydrant. In closing the main valve the pressure of the water forces the supplemental valve to close gradually with the main valve; but on account of the lost motion in the bell-crank the supplemental valve 95 will first come to its seat before the main valve has fully closed.

100 It will be seen that the operation of opening and closing the supplemental valve is thus

made perfectly automatic, and the desired subsequence in the opening and closing of the two valves (which is intended to prevent the wasting of water through the waste-orifice) is likewise accomplished, all as has been obtained heretofore; but my improved construction, while it does not change the *modus operandi*, has some specific advantages over other constructions, which I will now proceed to explain.

15 First. Heretofore the supplemental valve was placed in the vertical arm of the elbow, (just where I place the main valve,) and the main valve was placed above it. This brought the main valve much nearer the frost-line than 15 in my construction; therefore my construction presents a decided advantage in this respect.

Second. Heretofore the supplemental valve operated in a vertical position, and a spring was placed underneath it to counterbalance its 20 weight and assist in closing it. This arrangement necessitated a complication of parts, always liable to get out of order, for reasons well understood, and as the supplemental valve cannot be taken out and repaired with the same

25 facility as the main valve, it made the benefits sought to be derived from the use of a supplementary valve more or less illusory. In my construction, the valve is balanced without a spring simply by supporting it in a horizontal position, and therefore the valve is of the 30 simplest description, with little or no liability to get out of order.

Third. Heretofore the supplemental valve was never supported at all times in two stationary bearings. It was therefore liable to be displaced. In my improvement the valve-stem has two stationary bearings upon opposite sides of the valve, which always guide the valve and prevent it from being displaced 40 in any of its positions.

My improved waste-valve is arranged and constructed as follows: O is a waste-cock secured in the lower end of the hydrant-stock, so as to afford a waste-passage for the water from 45 the hydrant-stock to the exterior in the usual manner. The handle P, controlling this waste-cock, is provided with a slot, f, which engages with a pin, g, carried by a collar, R. The collar R being secured upon the valve-stem of 50 the main valve, the operation of opening or closing said main valve will therefore operate the handle of the waste-cock, all the parts being so arranged that the waste-cock will effect the same results obtained heretofore by other 55 devices—that is, the waste-orifice is kept open as long as no water is admitted to the hy-

drant, but is closed as soon as water is admitted by opening the valves. Heretofore a ring-valve secured to the valve-stem and arranged to close and disclose a waste-orifice in the wall 60 of the hydrant was used as a waste-valve, and this ring-valve was also used as a means for guiding the stem of the main valve. Instead of this I provide the lower end of the hydrant-stock with a bridge, S, supporting a brass 65 bushing with a square opening, through which the valve-stem, which is made square at this end, passes, and prevents the valve-stem from turning.

A perfect operation of the ring-valve for accomplishing the double duty of guiding the main-valve stem and operating as a waste-valve cannot be safely relied on under all circumstances, and therefore I consider my construction an improvement in this particular. 70

What I claim as my invention is—

1. In a fire-hydrant having a main valve and a supplemental valve, a supplemental valve located in the horizontal arm of the elbow, independent of the main valve and at right angles thereto, substantially as described.

2. In a fire-hydrant having a main valve and a supplemental valve, a supplemental valve supported and operating horizontally in the horizontal arm of the elbow at right angles to the main valve, substantially as described.

3. In a fire-hydrant, the combination of a main valve operating in the vertical axis of the elbow, a supplemental valve operating in the horizontal axis of the elbow, and a bell 90 crank or lever in the angle of the elbow, all arranged to operate as described.

4. In a fire-hydrant, the combination of a main valve operating on a vertical valve-stem in the vertical axis of the elbow, a supplemental valve operating on a horizontal valve-stem in the horizontal axis of the elbow, and a bell-crank in the angle of the elbow and provided with the lost motion described, all substantially as specified. 95

5. In a hydrant, the combination, with the main-valve stem provided with collar R, carrying pin g, of the waste-cock O, working in an aperture in the lower end of the hydrant, and the handle P to said cock provided with slot f, substantially as and for the purpose specified. 100

JOHN MEAD.
